UNITED STATES PATENT OFFICE.

GEORGE F. KUNZE, OF SLEEPY EYE, MINNESOTA, ASSIGNOR OF ONE-HALF TO
SOLOMON A. WOOLDRIK, OF SLEEPY EYE, MINNESOTA.

WRENCH.

1,110,445.

Specification of Letters Patent. Patented Sept. 15, 1914.

Application filed March 30, 1914. Serial No. 828,308.

To all whom it may concern:

Be it known that I, GEORGE F. KUNZE, a citizen of the United States, residing at Sleepy Eye, in the county of Brown and State of Minnesota, have invented certain new and useful Improvements in Wrenches, of which the following is a specification, reference being had to the accompanying drawings.

10 This invention relates to improvements in wrenches, and more particularly to that class of wrenches which are generally designated as "monkey wrenches".

An object of this invention is the provision of a wrench comprising a stationary jaw having a rearwardly extending shank connected thereto, and a sliding jaw which is provided with a rearwardly extending arm for sliding engagement with the shank 15 of the stationary jaw, the arm being threaded upon its outer face for engagement with the interior threads on the handle, whereby upon rotation of the handle, the threaded arm is moved longitudinally upon the shank 20 of the stationary jaw, to adjust the distance between the opposing faces of the jaws.

A further object of this invention is the provision of a wrench of this character which comprises a minimum number of 30 parts, whereby it may be cheaply manufactured, and a wrench which may be quickly operated and which will be very efficient in use.

With these and other objects in view, my 35 invention consists in the novel construction, combination, and arrangement of parts to be hereinafter more fully described, claimed, and illustrated in the accompanying drawing, in which,

40 Figure 1 is an elevation partly in section of my improved wrench; and Fig. 2 is a section on the line 2—2 of Fig. 1.

Referring more particularly to the drawing, the numeral 1 designates a stationary jaw to which is connected a rearwardly extending shank 2, the inner side face of 45 which is provided with a central longitudinal groove 3 which extends from a point adjacent the inner end of the shank to a point adjacent the head thereof, as clearly 50 shown in the drawing. The shank 2 is preferably oval in shape, and slidably mounted upon the shank is a sliding jaw 4, the inner extremity of the jaw having an angular slot 5 formed therein for the reception of

the angular reduced extension 6 formed on the forward end of a sliding arm 7 which is adapted for sliding engagement in the longitudinal groove 3 in the shank 2. To maintain the extension 6 of the arm 7 in 60 the angular slot 5, a band 8 is frictionally engaged over the inner end of the jaw 4 to inclose the slot 5 and prevent accidental disengagement of the extension 6 therefrom.

The outer face of the shank 2 is reduced at 65 the inner end of the slot as at 9, to form a shoulder 10 intermediate of the ends of the shank, and a ferrule 11 is engaged over the inner end of the shank to abut against the shoulder 10 and encircle the arm 7, the outer 70 face of which projects from the slot 3 in the shank, the ferrule being provided on its outer periphery with a rearwardly extending flange 12. The projecting face of the arm 3 is threaded as at 13, and a substantially cylindrical handle 14 is rotatably mounted upon the inner end of the shank 2, the outer end of the handle being interiorly threaded as at 15 for engagement with the threads 13 of the arm 7. The handle 14 is 75 also provided at its forward end with a forwardly extending annular flange 16 for engagement with the flange 12 of the ferrule, and to prevent longitudinal movement of the handle on the shank 2, a nut 17 is threaded 80 upon the inner extremity of the shank 2 to bear against the inner end of the handle.

In the operation of my improved wrench, when it is desired to close the jaws 1 and 4 against the work, the handle 14 is rotated in 90 the proper direction to move the arm 7 outwardly on the shank 2 by reason of the engagement of the threads of the arm and the handle, until the sliding jaw 4 contacts with the work, whereupon the wrench may 95 be used in the ordinary manner. When the wrench is used to turn a nut or the like the handle will be prevented from rotation due to the frictional engagement of the arm 7 in the groove of the shank, owing to the pressure upon the handle in turning the work. It will be seen that the various parts of the wrench are readily detachable, so that should any part of the wrench become mutilated or broken, it may be readily replaced.

Having thus fully described my invention, what I desire to secure and claim by Letters Patent, is:—

1. A wrench comprising a stationary jaw having a rearwardly extending shank, a 110

sliding jaw having an angular transverse slot formed in the inner end thereof, an arm slidably engaged upon said shank and having an angular extension at its forward end for engagement in said slot, a band mounted upon the inner end of said sliding jaw to inclose said extension in the angular slot, and a handle rotatably mounted upon the inner end of said shank and operatively engaged 15 with said arm, whereby upon rotation of said handle said sliding jaw will be moved longitudinally of said shank.

2. A wrench comprising a stationary jaw having a rearwardly extending shank projecting therefrom, the inner face of said shank having a longitudinally extending groove formed therein, a sliding jaw mounted upon said shank, said jaw having an angular transverse slot formed in the inner 20 end thereof, an arm slidably engaged in said groove, the forward end of said arm having an angular extension for engagement in said slot, a band mounted upon the inner end of said sliding jaw to inclose said extension in said angular slot, one face of said arm projecting outwardly of the groove and being threaded, and a handle rotatably mounted upon the inner end of said shank, said handle being interiorly threaded for 25 engagement with the threads on said arm, as and for the purpose described.

3. A wrench comprising a stationary jaw having a rearwardly extending shank projecting therefrom, said shank having a longitudinal groove formed in its inner face, a sliding jaw mounted upon said shank, the inner end of said jaw having a transversely extending angular slot formed therein, an arm having an angular extension at its forward end for engagement with the angular slot, said arm being slidably disposed in the longitudinal groove in the shank, the inner end of said shank being formed with a reduced portion on one side thereof forming a shoulder, a ferrule mounted on the reduced portion of said shank to engage the shoulder and encircle said arm, a handle rotatably mounted upon the reduced portion of said shank and having its inner end engaged with said ferrule, said handle being interiorly threaded for engagement with the threads on said arm, and means mounted on the inner extremity of said shank for engagement against the inner end of said handle to prevent longitudinal movement thereof upon said shank, as and for the purpose described.

In testimony whereof I hereunto affix my signature in the presence of two witnesses.

GEORGE F. KUNZE.
